HYDRAULICALLY POWERED MOTOR, PARTICULARLY ADAPTED FOR DEEP WELL PUMPING

Paul Gene Hart, 2613 Espanola St. NE.,
Albuquerque, N. Mex.
Filed Aug. 16, 1960, Ser. No. 49,971
4 Claims. (Cl. 121—129)

The present invention relates to hydraulic motors—that is, cylinder and piston type motors powered by liquid introduced thereto under high pressure. These generally are used in deep well oil pumping systems; and this motor has been especially designed for such use.

The motor of this invention is oscillatory in the sense that it involves a cylinder and coacting piston, working together in either straight-line or arcuate motion, with one or the other substantially stationary, located adjacent the well bottom and receiving oil or other liquid under high pressure from the earth's surface. Of course, the motor is suitable for other applications and installations.

It is noted that many patents have been granted for motors, and combined motor-pumps, for deep well operation; all being very costly to manufacture and requiring high maintenance costs even if operational for limited periods.

The primary object of the present invention is to produce and supply a simplified motor that is operable by hydraulic pressure, and specially designed to actuate deep well pumping mechanism; the principal idea being to provide a motor that is inexpensive, seldom requiring attention. Most motors of this type require a chain of intricate valves, pistons and cylinders; or a too-complex system of stationary cylinder, interposed sleeve valve and inner piston, all within a surrounding casing of small diameter.

The simplification, just mentioned, consists primarily in eliminating at least one part—utilizing the actual working cylinder itself as a chamber and also as the principal part of a reversing valve arrangement. There is a housing, this sleeve-valve cylinder working therein and a power piston connectible to any suitable machine, such as a pump, requiring mechanical operating power.

Another major object of this invention is to so design the ports and passages that the line for inlet flow is always greater in cross-sectional area than that for the outlet (exhaust) flow; the purpose of such design being to avoid liquid lock that might prevent valve reversal at the end of stroke. In the absence of positive reversing mechanism, this feature is deemed essential, and in any event it is helpful, as the device depends in great part upon inertia or "bounce" in its oscillatory motion to ensure valve reversal.

A further important object is to provide a check-valve means in the path of fluid flow through a ported piston in an arrangement of the type mentioned, for reasons soon to be understood.

The foregoing, and still further and subordinate objects will appear from a study of the following description when taken in conjunction with the accompanying drawings, wherein:

FIG. 1 illustrates, in longitudinal and vertical section, the preferred embodiment of my invention disposed in its most suitable environment, viz., at the bottom of a deep oil well.

FIG. 2 shows the motor of FIG. 1 in complete and enlarged longitudinal section, with the piston elevated for its down stroke.

FIG. 3 duplicates FIG. 2, except that the piston has terminated its down stroke and is being initiated to its return or up stroke.

FIGS. 4, 5 and 6 represent cross sections taken respec-

2

tively on lines 4—4, 5—5 and 6—6, FIG. 3, with all looking upwardly as indicated by arrows.

With continued reference to the drawings, and first to FIG. 1, the numeral 10 denotes a conventional deep well casing. It may be a few hundred, or several thousand feet underground. In fact, the motor M shown therein may be operated above the earth's surface. However, this motor M, specialized as shown, is designed for underground operation.

In the specialized application illustrated in FIG. 1, the casing 10 may have a diameter of only several inches. It follows that there is no room for additional internal parts, especially variegated valving arrangements, cylinder, piston, etc., so complicated as to introduce inter-locking, sanding, too-frequent pulling for repair, etc. Here the casing 10, of course, is in sections, screwed together, though not illustrated in that manner.

Likewise the motor M, though shown simply in the form of a bucket, may comprise two or more sections screw-threaded together, to form the cylinder housing 12. This is an outer container, very essential, for the working cylinder and piston of the motor parts, as it provides outflow passage of exhaust liquids into the space between tubes 13 and 17. It should be explained here that tube 13 exhausts liquid, and that tube 17 shoots high-pressure liquid to the motor proper from a pressure source.

Most of this can be understood by reference to the prior art, in which there are some engines of this general type. Some of them utilize hydraulic pressure developed aboveground. Some utilize the pumped oil in an interchange system.

The present invention relates to such mechanisms but actually resides in a motor classification. Therefore, in presenting it, not much attention has been given to operational details for deep well arrangements. For example, the members 13, 17 should have well known spacing and anchoring arrangements, and a pump could be shown in operation by the rod 14. In this connection, it should further be understood that suitable and known sealing means will be provided where the rod slides through the cylinder end, and at any other appropriate points or zones throughout the engine.

Looking now at FIGS. 2—6, an important part of the motor M comprises a traveling piston P, having its body 16 integrally or otherwise solidly connected by the rod 14 to a pump (not shown) or any mechanism adapted to actuation thereby. The cylinder C, however, is the basic unit of the motor. It is a working cylinder, and it functions as a sleeve valve; and comprises the core of the entire system of revolutionary, simple motor operation. It not only causes reversal of the piston strokes but aids in the introduction of high pressure fluid to one end of its own chamber.

The cylinder is double ended and entirely closed except for features now to be discussed. It is mounted for substantial but limited axial sliding movement within a pair of complementary members 18, one at each end of the housing 12, and joined to the latter, for example, by webs 19 and ribs 20. The members 18, functioning as part of an exhaust valving arrangement are shaped somewhat as the rim of a circular cake tin, open at their ends and receiving the cylinder for reciprocation within their cylindrical rim portions.

The cylinder C has an elongated body 22, provided adjacent each end with a circumferential series of exhaust ports 23, preferably narrow and elongated vertically. As seen in FIGS. 2 and 3, these ports are opened and closed by the members 18 as the cylinder assumes one or the other of its extreme positions within the limits of its reciprocation.

Just where it enters the cylinder, the feed tube 17 carries an enlarged pot 25, provided with a circumferential

set of ports 26, and the upper end of the cylinder has a down-turned cylindrical flange 24 to open and close this set of ports. Thus, the cylinder C operates to completely control the exhaust from both ends of its own working chamber, and to control the admission and cut off of high pressure fluid at its upper end.

The chambered pot 25 has a downward cylindrical portion 27, designed to abut and push down a valve member 30 of the piston P, as presently seen. The pipe 28 is secured to portion 27 but actually consists of an extension of the feed tube 17. It is of a length approximately equal to the stroke of the piston and is freely receivable by the hollow piston rod 14. At its lower end it has a flanged abutment or "kicker" 29 to force the piston valve unit 30 up at the end of the down stroke.

The piston P is a quite simple device comprising, as aforesaid, a reciprocating body 16. It is hollowed out centrally to slidably receive its valve unit 30, and the latter may be confined by a spanner type ring 32 screwed into the piston. The bottom of unit 30 has an annular offset ring 33b complementary to an annular recess 33a in the top of the piston rod to create a valuable dash pot effect when the valve is forced suddenly to its down position by the feed tube abutment 27. The cylinder body 22 has a pair of internal integral rings 34 for defining the two limits of the piston stroke.

The purpose of the valve unit 30 is to control a high pressure porting arrangement built into the piston, said arrangement comprising an annular cavity 35 within the piston and having a plurality of passages 36, leading downwardly therefrom into the bottom of the working chamber. This cavity is in communication with the feed tube when the valve 30 is "up" (FIG. 3).

Because of liquid displacement required by movement of the valve unit 30, in a system or incompressible fluid, it is desirable to provide the piston with check valve units 38 and 39, openable in opposite vertical directions to relieve pressure at one side of the piston or the other.

It is considered highly essential that the inlet port area for each end of the piston stroke be greater than the total exhaust port area for that part of the cycle of operation. This can be done by properly sizing and shaping the ports. The illustrated design is capable of many variations within the scope of the invention.

A preferred embodiment of this invention is found in FIGURE 2 and FIGURE 3. In this embodiment piston 16 is moved by fluid pressure from the lower cylinder chamber, as shown in FIGURE 3, to the upper cylinder chamber, as shown in FIGURE 2, by the following method. Fluid under pressure enters the cylinder chamber through tube 28. The lower exhaust ports 23 are closed by the lower complementary members 18. Piston 16 and valve unit 30 are moved upward in the cylinder chamber by the fluid pressure. Valve unit 30 is contacted by kicker plate 27, stopping the movement of valve unit 30 but allowing piston 16 to continue moving forward to contact the upper internal integral ring 34, causing the cylinder to move upward moving down-turned cylindrical flange 24 into an upward position thereby opening inlet ports 26. As the cylinder moves forward upper exhaust ports 23 are closed by upper complementary members 18 and the lower exhaust ports 23 are opened by the upward movement of the cylinder from lower complementary members 18. The entry of fluid under pressure to the cylinder chamber through tube 28 is shut off by valve unit 30 closing the opening between piston 16 and rod 14 as shown in FIGURE 2.

As ports 26 are opened the fluid under pressure enters the chamber through ports 26 causing piston 16 to move in a downward direction toward the lower portion of the cylinder chamber. Exhaust of the fluid is accomplished through lower ports 23 as previously explained.

Piston 16, as it approaches the lower position, as shown in FIGURE 3, contacts the lower integral ring 34 forcing the cylinder chamber down, thereby closing exhaust ports 23, closing the upper inlet ports 26, and opening the upper exhaust ports 23, thereby allowing the direction of the piston to be reversed and the piston to again proceed in its upward course.

The method of operation should now be fairly obvious from the foregoing running description, so no elaborate dissertation should be necessary. The principal feature to be observed is that the cycle of operation is fully automatic as long as sufficiently high pressure is supplied and that at the end of each stroke, aided by momentum the cylinder moves a short distance to change the porting and thus reverse the direction of stroke.

Obviously, the apparatus illustrated and described is susceptible to many modifications, especially as to detail, by those skilled in the art without departing from the spirit of the invention.

What is claimed is:

1. In combination with a well casing and a housing having a fluid discharge means; a working cylinder slidably axially within the housing, the cylinder having both ends ported for exhaust, a valve means attached to the upper end of the cylinder, a power piston fitted within the cylinder chamber for reciprocation under alternate pressure of a fluid, a valve means attached to the piston, an inlet means for fluid under pressure with port communication to the upper and lower portions of the cylinder chamber, a pair of complementary members within the housing at the upper and lower end position of the axially slidable cylinder, whereby the piston is reciprocated by the inlet of fluid pressure which is alternately controlled by the valve means attached to the piston at the lower portion of the cylinder chamber and by the valve means attached at the upper portion of the cylinder chamber and the exhaust of the pressure fluid is alternately controlled by the closing of the cylinder ports by the complementary members as the cylinder is moved axially to its upper and lower position within the housing by the reciprocating piston.

2. In the combination of claim 1, the inlet and exhaust arrangements so designed that, in either direction of the piston stroke, the total area of the inlet ports exceeds that of the corresponding discharge ports.

3. In the combination of claim 1, the piston having a rod attached thereto, said rod extending outwardly through the opposite end of the housing, an internal chamber within the rod at least the length of the piston stroke with intercommunication with the lower cylinder chamber, an inlet means for fluid under pressure at the lower portion of the cylinder consisting of a feed tube with an inlet port at the end, the tube the length of and projecting into the rod chamber, the tube having a stationary abutment block mounted near the top of the piston stroke to engage the valve member attached to the piston causing it to close the internal piston chamber thereby stopping the pressure fluid flow through the feed tube.

4. In the combination of claim 1, the working cylinder having two internal integral rings located at opposite portions of the cylinder whereby the axially slidable motion of the cylinder is caused by the contact of the piston with the rings as it moves within the cylinder.
